US00D629090S

(12) **United States Design Patent**
Quinn et al.

(10) **Patent No.:** US D629,090 S
(45) **Date of Patent:** ** Dec. 14, 2010

(54) **AIR DRYER**

(75) Inventors: **Leonard A. Quinn**, Lagrange, OH (US);
Gregory Ashley, Amherst, OH (US)

EP 214373 A1 3/1987

(73) Assignee: **Bendix Commercial Vehicle Systems LLC**, Elyria, OH (US)

(Continued)

(**) Term: **14 Years**

(21) Appl. No.: **29/366,036**

(22) Filed: **Jul. 19, 2010**
